ANNEALING FURNACE STRUCTURE

Clarence B. Hoak, Steubenville, Ohio

Application March 3, 1936, Serial No. 66,932

7 Claims. (Cl. 266—5)

My invention relates generally to annealing furnace structure especially adapted to the heat treating of sheet steel and tin and incorporating special features insuring proper distribution of the heat to the top, bottom, and sides of the material while in the annealing chamber, and in a manner to positively prevent oxidizing of the material being annealed, and an important object of the present invention is to provide annealing structure of the character indicated whereby either a sectional or an integral annealing furnace may be constructed and operated efficiently, either the furnace as a whole or the sections thereof being readily portable by suitable cranes or hoists, and transported from place to place as needed.

Another important object of the present invention is to provide improvements in structure and in function over the subject matter set forth in my co-pending application Serial No. 26,049, filed June 11, 1935, now Patent No. 2,040,994 dated May 19, 1936, and entitled Annealing furnace, in the regards of better and more efficient provision for circulation of and use of the heating gases and products of combustion, in better use of the heat through provision of heat absorbing and radiating partitions between the combustion chambers and the annealing chamber, and in providing improved materials for the partitions as well as more efficient structure thereof, and other provisions which will appear in the following description of the drawings.

Another important object of the invention is to provide partition means defining the combustion chambers and the annealing chamber which not only act as conduits for the gases and products of combustion from the burners, but act as means to radiate heat into the annealing chamber, by conduction and convection to increase the use of the heat generated by the burners in the combustion chambers and produce better distribution of the heat in the annealing chamber; by providing sectional partition structure in which the sections have thinner walls with smaller overlapping portions and greater surfaces in contact with the products of combustion in the combustion chambers and with the atmosphere in the annealing chamber; the said sections being arranged and placed with respect to each other to allow for expansion and contraction.

Other important objects of the present invention will be apparent from a reading of the following description in connection with the drawings, wherein for purposes of illustration I have

shown preferred embodiments of the present invention.

The present application constitutes a continuation in part of the co-pending application mentioned above.

In the drawings:

Figure 1 is a general side elevational view of one embodiment of my invention.

Figure 2 is a transverse vertical sectional view taken through Figure 4 approximately on the line 10 2—2.

Figure 3 is a horizontal sectional view taken through Figure 1 approximately on the line 3—3 and looking downwardly in the direction of the arrows.

Figure 4 is a transverse vertical sectional view taken through Figure 1 or 2 approximately on the line 4—4 and showing the hood without the base.

Figure 5 is an elevational view of one of the partition sections.

Figure 6 is a transverse vertical sectional view taken through Figure 5 approximately on the line 6—6.

Figure 7 is a top plan view of Figure 6.

Figure 8 is a group horizontal sectional view showing adjacent partition sections and illustrating the manner in which they inter-engage to form the partition.

Figure 9 is a perspective view of one of the covers.

Figure 10 is a bottom plan view of one of the platforms.

Referring in detail to the drawings, the numeral 5 generally designates the hood of the furnace which may be cruciform in plan and dome-shaped in cross section as shown or assume any other suitable size and shape and be composed of an outer metal shell 6 having a hoisting handle 7 at its top and have inwardly extending from its lower edges the annular flange 8 which rests on the floor 9 of the base 10, so that the hood is thereby separable from the base and can be lifted therefrom. Burner openings 11 are distributed circumferentially around the lower side walls of the hood, any suitable number of these burner openings 11 being located in each arm or wing 12 of the hood which has the cruciform or other suitable shaped horizontal cross section illustrated in Figure 3.

Each arm 12 of the hood has its interior lined with suitable refractory material structure, the walls of which are severally and respectively designated by the numerals 13, 14, 15 and 16, being the opposite side walls, the radially outward wall,

and the bottom wall. The radially outward wall 15 arches across the top of the shell and forms the top boundary of the annealing chamber as well as of the respective combustion chambers defined by the mentioned walls and the respective partitions each of which is generally designated 17.

Each partition is composed of a plurality of tiers in side by side relation, each tier being composed of vertically superposed sections 18, 19 and 20, and a desirable number of tiers is used in each partition 17, the tiers being juxtaposed and interlocked in a manner to be pointed out.

Each of the tier sections is in the form of a body of heat resisting metal or of refractory material suitable to radiate and conduct heat from the combustion chamber to material being heated, the body being triangular in cross-section 21 having a triangular cross-section bore 22 defining relatively thin acutely angulated walls 23 and 24 and the annealing chamber wall 25 which in the case of the upper and lower sections 18 and 20, respectively, have at the proper level the gas passing openings 26 and 27 and between them the solid part having the vertical bore 28 which is provided to receive the assembling bolt 29 which has a head 30 embedded in the lower end of the bottom tier section on a level with the lower gas passages 52 and a threaded upper portion passing through a boss 31 on the upper side 30 of the shell 6, as shown in Figure 4, and accommodating a nut arranged to bear against the top of the boss 31.

The lower tier section 18 is provided in its top with a socket telescopically receiving the reduced portion 32 on the lower end of the intermediate tier section 19; and the section 19 has a socket 33 in its upper end receiving the reduced lower end of the upper tier section 20. The lower end of the lower tier section 18 is squared, while the upper end of the upper section 20 is beveled to conformably engage the inner surface of the refractory wall 15.

One end of the wall 25 of each of the sections is pointed as indicated by the numeral 35 while the opposite end is notched as indicated by the numeral 36, both formations extending the full height of the respective section. The points 35 are engaged with the notches 36 in juxtaposing and assembling the various tiers of sections to 50 form the respective partitions 17.

The base 10 has within the annealing chamber defined by the radially inward sides of the described tiers the raised refractory material transverse generally parallel portions 37 and 38, 55 thereby defining two separate supports for the annealing stands with a transverse passage therebetween which has therealong a plurality of vertical exhaust outlet openings 39 which traverse the base as indicated in Figure 2. Any suitable number of annealing stands may be used 60 with corresponding obvious rearrangements and enlargements of the base and hood structure.

Imposed on each platform 37, 38 is an annealing stand 40, 41 which is composed of suitable material in the form of a plate 42 from which depend conical legs 43 which space the plate 42 above the respective platform and permit free circulation of the gases under the plate 42.

Imposed on each annealing stand is a respective cover 44, 45 enclosing a respective stack 46, 47 of the sheet material being treated and annealed, in the manner and form already disclosed in my above mentioned prior patent, wherein each cover is provided on its sides with 70 downwardly tapering flanges 48 which have at-

tached to the outer lower edge thereof the sand retaining rim 49 which retains a quantity of sand or the like 50 to absolutely prevent passage of any air or fluids between the top of the stand and the lower edge of the cover, thereby preventing the possibility of any oxidizing of the contents of the cover.

In accordance with the present invention the burner openings 11 are re-located and placed in the hood instead of in the base as in the said patent, so as to achieve among other advantages, the feature of having the burner openings in the hood so as to be transportable with the hood instead of being in the base and remaining in the base when the hood is transported as is the case 15 with the arrangement shown in the said patent.

In accordance with the present invention the burners playing into the combustion chambers through the burner openings 11 fill the interior of the combustion chambers with gases and products of combustion, and these products of combustion rise in the combustion chambers and pass into the elevated openings 51 in the radially outward side of the upper partition section 20 of the tiers and then pass downwardly through the 25 bores of the tiers to and through the openings 52 which are on a level with the lower side of the plates 41 of the annealing stands and are larger than the openings 53; and some of the gases moving in the bores of the tiers pass upwardly and 30 into the upper part of the annealing chamber through the elevated openings 53. This arrangement or distribution of the heating gases not only provides proper circulation of the hot gases at 35 the lower part of the combustion chamber, but the provision of the elevated openings 53 in the upper parts of the partitions provide for distribution of the hot gases at the upper part of the annealing chamber, thereby effecting a much improved distribution of the gases procuring greater heating 40 efficiency and greater uniformity of heat in the annealing chamber.

The partitions being of heat resisting metal or of refractory material suitable to conduct and radiate heat, the heat in the combustion chambers is embodied in the partition and radiated into the annealing chamber, so that the annealing chamber has heat radiated therein for the full height thereof not only by conduction through the partitions, but also by convection by 50 reason of the movement of the gases into the annealing chamber through the partition openings 52 and 53. The present form of the tiers composing the partitions is such as to present a maximum surface area absorbing, conducting 55 and radiating heat from the combustion chamber to the annealing chamber. The form and arrangement of the tiers also provide for expansion and contraction, and the method of mounting the sections into tiers, and the tiers into partitions 60 enables easy removability thereof for replacement when necessary.

It is desired to expressly mention as within the scope of the invention the elongation of the furnace shown and described herein to any suitable length and size, and the provision of any desired or suitable number of burner openings and flues and flue openings, and stands enabling adapting the device shown and described with-out invention to particular circumstances.

Although I have shown and described herein preferred embodiment of my invention, it is to be definitely understood that I do not desire to limit the application of the invention thereto, and any change or changes may be made in the 75

materials, and in the structure and arrangement of the parts, within the spirit of the invention and the scope of the subjoined claims.

What is claimed is:

5. 1. An annealing furnace comprising a base provided centrally with exhaust openings, a hood resting on said base and formed in the side wall thereof with burner openings, tubular vertical partitions in said hood, said partitions being arranged relative to said hood to define combustion chambers in direct communication with said burner openings and an annealing chamber in direct communication with said exhaust openings, said partitions being formed with first openings adjacent their upper ends whereby communication is established between said combustion chambers and the interior of said partitions, said partitions being formed with vertically spaced second and third openings establishing communication between the interior of the partitions and said annealing chamber, said second openings being located adjacent the upper end of said partitions so as to positively circulate the products of combustion over and around any material spacedly supported on said base in said annealing chamber, said third openings being located adjacent the lower end of said partitions so as to circulate additional products of combustion around and under the lower part of the material in the annealing chamber, whereby uniform heating of the material is procured.
2. In an annealing furnace, a base provided centrally with exhaust openings, a hood resting on said base and formed in the side wall thereof with burner openings, tubular vertical partitions in said hood, said partitions being arranged relative to said hood to define combustion chambers in direct communication with said burner openings and an annealing chamber in direct communication with said exhaust openings, said partitions being formed with first openings adjacent their upper ends whereby communication is established between said combustion chamber and the interior of said partitions, said partitions further being formed with vertically spaced second and third openings establishing communication between the interior of said partitions and said annealing chamber, said second openings being located adjacent the upper ends of said partitions so as to positively circulate the products of combustion over and around any material spacedly supported on said base in said annealing chamber, said third openings being located adjacent the lower ends of said partition so as to circulate additional products of combustion around and under the lower part of the material in the annealing chamber, said tubular vertical partitions comprising conduits of substantially triangular cross section each arranged with two sides exposed in said combustion chamber and the remaining side exposed in said annealing chamber.
3. An annealing furnace comprising a base provided centrally with exhaust openings, a hood resting on said base and formed in the side wall thereof with burner openings, tubular vertical partitions in said hood, said partitions being arranged relative to said hood to define combustion chambers in direct communication with said burner openings and an annealing chamber in direct communication with said exhaust openings, said partitions being formed with first openings adjacent their upper ends whereby communication is established between said combustion chambers and the interior of said partitions, said partitions being formed with vertically spaced second and third openings establishing communication between the interior of said partitions and said annealing chamber, said second openings being located adjacent the upper ends of said partitions so as to positively circulate the products of combustion over and around any material spacedly supported on said base in said annealing chamber, said third openings being located adjacent the lower ends of said partitions so as to circulate additional products of combustion around and under the lower part of the material in the annealing chamber, said tubular vertical partitions comprising conduits of substantially triangular cross section arranged with two sides thereof exposed in said combustion chamber and with its remaining side exposed in said annealing chamber, each conduit comprising a plurality of vertically superposed sections, and assembling means traversing the sections and assembling the same.
4. An annealing furnace comprising a base provided centrally with exhaust openings, a hood resting on said base and formed in the side wall thereof with burner openings, tubular vertical partitions in said hood, said partitions being arranged relative to said hood to define combustion chambers in direct communication with said burner openings and an annealing chamber in direct communication with said exhaust openings, said partitions being formed with first openings adjacent their upper ends whereby communication is established between said combustion chambers and the interior of said partitions, said partitions further being formed with vertically spaced second and third openings establishing communication between the interior of said partitions and said annealing chamber, said second openings being located adjacent the upper ends of said partitions so as to positively circulate the products of combustion over and around any material spacedly supported on said base in said annealing chamber, said third openings being located adjacent the lower ends of said partitions so as to circulate additional products of combustion around and under the lower part of the material in the annealing chamber, said tubular vertical partitions comprising conduits of substantially triangular cross section arranged with two sides thereof exposed in said combustion chamber and with its remaining side exposed in said annealing chamber, said conduit means comprising a plurality of vertically superposed sections, assembling means traversing the sections and assembling the same, said assembling means comprising a vertical rod passing through the superposed sections and having a head on its lower end acting as an abutment for the lower end of the lowermost section, the upper end of said rod traversing the top of the hood, and fastening means holding the upper end of the rod and the upper end of the uppermost conduit section assembled relative to the top of the hood.
5. An annealing furnace comprising a base provided centrally with exhaust openings, a hood resting on said base and formed in the side wall thereof with burner openings, tubular vertical partitions in said hood, said partitions being arranged relative to said hood to define combustion chambers in direct communication with said burner openings and an annealing chamber in direct communication with said exhaust openings, said partitions being formed with first openings adjacent their upper ends whereby communication is established between said combustion chambers and the interior of said partitions, said partitions being formed with vertically spaced second and third openings establishing communication between the interior of said partitions and said annealing chamber, said second openings being located adjacent the upper ends of said partitions so as to positively circulate the products of combustion over and around any material spacedly supported on said base in said annealing chamber, said third openings being located adjacent the lower ends of said partitions so as to circulate additional products of combustion around and under the lower part of the material in the annealing chamber, said tubular vertical partitions comprising conduits of substantially triangular cross section arranged with two sides thereof exposed in said combustion chamber and with its remaining side exposed in said annealing chamber, each conduit comprising a plurality of vertically superposed sections, and assembling means traversing the sections and assembling the same.

tion chambers and the interior of said partitions, said partitions being further formed with vertically spaced second and third openings establishing communication between the interior of said partitions and said annealing chamber, said second openings being located adjacent the upper end of said partitions so as to positively circulate the products of combustion over and around any material spacedly supported on said base in said annealing chamber, said third openings being located adjacent the lower end of said partitions so as to circulate additional products of combustion around and under the lower part of the material in the annealing chamber, said partitions comprising conduit means of substantially triangular cross section having two sides exposed in said combustion chambers and with their remaining side exposed in said annealing chamber, said conduit means being arranged in side by side relation with the edges of its annealing chamber side engaged with the similar edges of the adjacent conduit means on either side thereof.

6. An annealing furnace comprising a base provided centrally with exhaust openings, a hood resting on said base and formed in the side wall thereof with burner openings, tubular vertical partitions in said hood arranged relative to said hood to define combustion chambers in direct communication with said burner openings and an annealing chamber in direct communication with said exhaust openings, said partitions being formed with first openings adjacent their upper ends whereby communication is established between said combustion chambers and the interior of said partitions, said partitions being further formed with vertically spaced second and third openings establishing communication between the interior of said partitions and said annealing chamber, said first openings being located adjacent the upper end of said partitions so as to positively circulate the products of combustion over and around any material spacedly supported on said base in said annealing chamber, said second openings being located adjacent the lower ends of said partitions

cent the lower ends of said partitions so as to circulate additional products of combustion around and under the lower part of the material in the annealing chamber, said vertical partitions comprising conduit means of substantially triangular cross section arranged with its apex and the adjacent two sides exposed in the combustion chambers and with the remaining side thereof exposed in said annealing chamber, adjacent ones of said conduit means thereof being arranged in side by side touching relation, the touching corners of said conduit means having complementary interlocking formations whereby relative shifting of said conduit means is prevented.

7. An annealing furnace comprising a base provided centrally with exhaust openings, a hood resting on said base and formed in the side walls thereof with burner openings, tubular, vertical partitions in said hood, said partitions being arranged relative to said hood to define combustion chambers in direct communication with said burner openings and an annealing chamber in direct communication with said exhaust openings, said partitions being formed with first openings adjacent their upper ends whereby communication is established between said combustion chambers and the interior of said partitions, said partitions being further formed with vertically spaced second and third openings establishing communication between the interior of said partitions and said annealing chamber, said second openings being located adjacent the upper ends of said partitions so as to positively circulate the products of combustion over and around any material spacedly supported on said base in said annealing chamber, said third openings being located adjacent the lower ends of said partitions

CLARENCE B. HOAK. 45
